UNITED STATES PATENT OFFICE

JOSEPH POSPISIL, OF BLOOMFIELD, NEW JERSEY, ASSIGNOR TO LAUTER-HUMANA CO.,
A CORPORATION OF NEW JERSEY

DESIGN FOR A PIANO LIGHT OR SIMILAR ARTICLE

Application filed August 26, 1931. Serial No. 40,934. Term of patent 7 years.

To all whom it may concern:

Be it known that I, JOSEPH POSPISIL, a citizen of the United States, and a resident of Bloomfield, in the county of Essex and State of New Jersey, have invented a new, original, and ornamental Design for a Piano Light or Similar Article, of which the following is a specification, reference being had to the accompanying drawing, forming part thereof.

Figure 1 is a perspective view of a piano light embodying my new design.

Figures 2 and 3 are respectively a side elevation and a bottom plan view of the piano light on a reduced scale.

I claim:

The ornamental design for a piano light or similar article, as shown.

JOSEPH POSPISIL.
